METHOD AND APPARATUS FOR SURFACE GRINDING METAL STRIP

Le Roy R. Valette, Pittsburgh, and William C. Safford, Industry, Pa., assignors to Crucible Steel Company of America, Pittsburgh, Pa., a corporation of New Jersey

Application July 16, 1953, Serial No. 368,374

16 Claims. (Cl. 51—5)

This invention pertains to improvements in grinding apparatus for the surface grinding and removal of surface defects from metal strip, such, for example, as long lengths of steel strip of sufficient thinness to permit of coiling onto reels, and in widths which may vary from a few inches up to 50" or 60" or more.

In the hot rolling of a metal breakdown into long lengths of relatively thin strip, surface defects, such as slivers, are often produced as a result of the rolling operation. Such defects are not removed by subsequent pickling and cold rolling, but are carried through as surface defects of the finished cold rolled product. In the production particularly of high grade alloy steel strip, such, for example, as the 18-8 chromium-nickel or the straight chromium stainless varieties, such as are employed for trim in the automotive, building industries, etc., it is essential that the cold rolled and finished product have a smooth, unmarred surface of high luster, entirely free from all surface defects. It is accordingly frequently necessary in order to obtain a surface of this character in the finished cold rolled product, that all surface portions of the hot rolled strip be subjected to roughing and finishing grinds, prior to finish cold rolling.

Grinding units heretofore employed for such purposes have in general been of the single-stand variety in which the strip is fed from a payoff reel between a pair of driven rolls, about one of which an abrading belt passes, the opposite roll serving as a backing up roll, thus to surface grind one side of the strip, which passes thence onto a windup reel. Grinding units of this character are expensive and cumbersome in operation due to the fact that each pass through the grinding unit requires unreeling and reeling the strip, and transporting the reeled unit back to the payoff reel for each successive pass through the grinder. Frequently a half dozen such passes are required properly to surface grind and finish each side of the strip, or a total of approximately a dozen or so passes in all.

In contrast to the above, the improved grinding apparatus of the present invention comprises a multiplicity of grinding units arranged seriatim, through which the strip is progressively and successively fed, from a payoff reel disposed at the entrance to the multi-stand grinding assembly and thence onto a coiling reel at the delivery end thereof. In accordance with various aspects of the invention, the grinding units may be of the conventional abrading belt variety or may comprise a series of abrading rolls or a combination of abrading rolls and abrading belts, and may be arranged to surface grind one or both sides of the strip as it passes through the multi-stand grinding assembly aforesaid.

The initial abrading stands of the sequence may thus be arranged to provide roughing grinds and the remainder of the sequence, finishing grinds of varying degrees of impression, so that in a single pass through the multi-stand sequence, the strip is both rough and finish ground, and thus emerges ready for pickling and cold rolling. If both sides are surface ground concurrently, the strip need be

2

unreeled and reeled but once; while if only one surface at a time is ground, only two unreeling and reeling operations are involved.

By the provision of a sufficient number of the grinding stands in sequence, for example, six in accordance with the preferred embodiment of the present invention, the abrading elements in certain of the stands may normally be disengaged from the strip while the remainder are grinding, so that in the event one of the stands which is effecting the grinding requires disengagement for repairs or for changing an abrading belt, one of the normally idle stands may be engaged during the interim, thus to assure uniformity in the grinding operation throughout the entire strip length. The apparatus of the invention thus provides extreme flexibility of operation in this respect, and also in the respect that one, two or more or all stands may be caused to engage the strip during a given grinding operation, depending on the extent of surface grinding required for that particular length.

Each of the grinding units, in the preferred embodiment thereof, comprises in tandem, a pair of entry pinch rolls, an abrading roll or contact roll carrying an abrading belt, together with an associated pressure roll, and an exit hold-down roll, these rolls being positioned for rotation about horizontal axes. To facilitate the threading of the leading strip end of a coil through the grinding unit, one of the pinch rolls is mounted for retraction with respect to its opposed pinch roll; and likewise the pressure roll is mounted for retraction with respect to its opposed abrading roll. After the strip end is threaded through the grinding unit, these rolls are advanced into their operative positions for resiliently pressing the strip against the opposed pinch and abrading rolls, respectively. In the preferred embodiment, this retraction and advancement of the pinch and pressure rolls is rapidly effected by means of hydraulic cylinder and piston assemblies.

Also in the preferred embodiment the pressure and abrading rolls are disposed slightly above the pass line of the entry pinch and exit hold-down rolls, in order 40 arcuately to flex the strip over the pressure roll, thus to provide a substantially tangential area of contact between the abrading roll and the strip surface contiguous thereto, thus to assure uniform surface grinding of all portions of the strip.

Fine or micrometer adjustments are provided in the mounting for the pressure roll of each grinding unit, for adjusting the same relative to the associated abrading roll in accordance with the thickness of strip being ground, and also for purposes of axially aligning the pressure roll, in absolute parallelism with the associated grinding roll. Various novel features are embodied in the mounting and adjustments of the pressure roll, as will more fully appear hereinafter in the detailed description relative thereto.

The entry pinch rolls of each grinding unit are further provided with disengageable braking means, for applying braking action thereto as the trailing end of a coil of strip being ground, passes off the payoff reel and successively thence through the grinding units, the so-braked pinch rolls serving thus to maintain tension on the strip between the successive grinding units and the windup or recoiling reel.

In the preferred embodiment there is also interposed between the payoff reel and the first grinding unit of the sequence, a levelling unit of novel construction, comprising a series of lower rolls, having opposed thereto in intercalated or staggered relation, a series of upper rolls, together with a pair of entry pinch rolls and a pair of entry guide rolls, the latter being rotatable about the vertical axes for centering the strip in the leveller. The opposed intercalated rolls serve to straighten the strip as it is fed therethrough. The upper levelling rolls are ar-

ranged to be individually elevated and depressed relative to their associated lower rolls, and the same is true of the upper entry pinch roll. The levelling and pinch rolls are arranged to be motor driven. For feeding an advancing strip end through the leveller and into the first grinding unit, the upper pinch and leveling rolls are depressed and all rolls are driven. After the strip is fed completely through the apparatus from the payoff reel onto the recoiling reel, the upper rolls of the leveler are either elevated away from the strip, or are thereafter arranged to function merely as idler rolls, since the power applied for driving the recoiling reel suffices to feed or pull the strip through the entire grinding line from the payoff reel, and since also the resulting tension thus applied to the strip thereafter suffices for straightening or flattening purposes. For thus controlling the tension on the strip, the payoff reel motor is arranged for optional driving or regenerative braking, and is regeneratively braked after the leading strip end has been fed onto the recoiling reel and driving power applied thereto.

Other important features of the invention reside in special provisions for safety and operation and adjustment of the several units and for individual and integrated driving and control means for the several units, whereby efficiency and safety are greatly enhanced.

Further objects and advantages of the invention will more fully appear from the following description taken in connection with the accompanying drawings which show, by way of example, a presently preferred embodiment and certain modifications of the invention.

Referring to the accompanying drawings in which the same reference characters indicate the same parts in the various views:

GENERAL DESCRIPTION

Referring now to the drawings and more particularly to Figs. 1 and 2: the apparatus therein comprises in general a payoff reel unit A, a leveller unit B, a sequence of six grinding units individually designated C1—C6, inclusive, arranged seriatim or in tandem as shown, a scrubber D, a wiper unit E and a windup reel unit F. In addition to these main units there are provided suitable electric, hydraulic and pneumatic motors, together with controls therefor grouped at stations located at convenient positions adjacent the entry end of the apparatus, at each grinding unit and at the delivery end, all being integrated to facilitate operation. The control stations are disposed as follows: Main stations I and II are located adjacent the delivery and entry ends, respectively, and a series of stations III are located adjacent respective of the grinder units C1—C6, inclusive.

The payoff reel unit A comprises a payoff reel 22, for mounting a coil of strip 23 on the reel shaft, which is coupled to a motor 21a optionally operated as a motor or drag generator, and thus adapted either to drive or brake the shaft. A blocker hoist 24 is provided adjacent the payoff reel shaft to facilitate mounting the coil 23 on the reel shaft as explained below.

Next in the sequence is the strip leveller unit B which comprises a guide roll 29, a pair of spaced apart vertical centering rolls 30, an upper series 33 and a lower series 32 of levelling rolls between which the strip S passes for straightening purposes. These rolls are arranged to be driven or idled as desired at various stages of the grinding operation, having associated therewith for such purposes a drive motor 62 coupled to the rolls. Likewise, the upper series of rolls 33 are mounted in bearing blocks, vertically displaceable in guideways by means of suitable electric motors 43a to be hereinafter described, for raising the upper rolls off the strip once it has been fed through the assembly line. Driven pinch rolls 55—56 are provided for feeding the strip to the levelling rolls and are separable by fluid motors 58 to permit free passage.

Next in the sequence is the series of grinding units C1—C6, each of which comprises in substance a pair of entrance pinch rolls, such as 86—87, between which the strip is fed, and the upper roll being provided with fluid actuated brake means to produce a drag on the strip, and the lower roll being retractable, at certain conditions of operation, as above mentioned. Beyond the pinch rolls, in the direction of the strip path, are a pair of rolls 89 and 92, one of which comprises an abrading roll or an abrading belt contact roll, such as 92, the opposite roll 89 functioning as a backing up or pressure roll. In certain modifications of the invention, the upper roll is the

abrading roll or abrading belt contact roll, while the lower or pressure roll is arranged for vertical displacement toward and away from the strip, thus to be elevated and engage the strip during grinding, and to be dropped well below the strip pass line to facilitate feeding the leading strip end of a new coil through the grinding unit. At the exit of each grinding unit there is mounted a holddown roll, such as 90, the function of which in conjunction with the entrance pinch rolls 86-87 is to flex the strip arcuately over the backing up roll, thus to provide a tangential line of contact transversely of the strip between the strip surface being ground and the upper abrading contact roll engaging the same for grinding purposes.

The strip on emerging from the last of the grinding units, e. g., C6, passes thence through a scrubber unit D for removing grit, sludge, grinding compounds and the like from the strip, and thence through a wiper unit E for removing excess scrubbing fluid, from whence the strip passes onto a driven windup reel 184 on which the ground strip S is wound into a coil 186.

PAYOUT UNIT A

Referring now to Figs. 3-6, inclusive, the payoff reel unit A comprises a main frame 21 and a motor-drag generator 21a suitably connected through a reduction gear train 21b-21c to a reel shaft 22a for driving or braking a payoff reel 22. The payoff reel is of the conventional expandible segment type actuated by a conventional hydraulic mechanism 22b-e, inc., for expanding and gripping the coil 23 of strip S to be surface ground. Adjacent the payoff reel there is provided (Fig. 1) a coil hoist 24 having mounted thereon a pair of hoist blocker rolls 24a, on which the coil 23 of strip S is rotatably supported preparatory to mounting on the reel 22. The coil hoist is raised and lowered by conventional hydraulic ram and cylinder means mounted below the floor line as described below. Adjacent the coil hoist is an inclined ramp 26 provided with elevatable floor chocks (not shown) for rolling the strip coil 23 onto the hoist blocker rolls. By a conventional hydraulic means, such as cylinders 25, 25', Figs. 4 and 6, and pistons, as at 25a, operating therein as shown, the reel 22 can be moved axially in and out to receive the coil 23 from the hoist 24, and to line the coil up with the grinding line equipment. To this end the entire coiler assembly is slidably mounted on wear plates, as at 25b, one on each side, and is axially displaced in and out by oil pressure and discharge lines interchangeably connectible through a 4-way valve, as explained below, to the opposite end, respectively, of cylinders 25, 25', thus to displace these cylinders relative to their associated pistons, which latter are pin connected, as at 25c, to fixed supports, as at 25d.

An important safety feature of the invention embodied in this unit is the provision of an arcuate arm 27 (Figs. 3 and 4) which extends in a direction transverse the axis of a coil 23 and disposed intermediate its ends. The arm 27 comprises side plates between which are pivotally mounted a main roller 27a adjacent its forward end, intermediate rollers 27b and 27c in spaced relation along the arm and a pair of rollers 27d on a rear extremity disposed beyond the axis of a torque shaft 27e to one end of which the arm is fixed. The rollers 27a-27d, inclusive, have their axes generally parallel to the axis of reel 22 and are spaced apart along an arcuate path preferably having a larger radius than the radius of coil 23. The rollers are so disposed that when roller 27a engages coil 23 the other rollers are progressively spaced from said coil while the strip is being fed forward and serve to restrain outward movement of a loose strip end. The shaft 27e is suitably journaled on the frame 21 and adjacent its opposite end carries fixed thereto a crank arm 27f to the outer end of which is pivotally connected a piston rod 27g of a pneumatic motor designated 27h. This motor is operated by a suitable control valve, to be hereinafter referred to, conveniently positioned at the entry end.

LEVELER UNIT B

From the coil 23 (Fig. 2) the leading end of the strip S thereof is fed to the leveller unit B. The latter comprises, as shown in Figs. 7-10, inclusive, an entry guide roll 29, disposed as shown, for engaging the strip S when the coil 23 becomes reduced sufficiently in diameter during the unreeling operation. At the entrance of the leveller there is also provided a pair of oppositely disposed and vertically arranged guide rolls (Fig. 9), such as 30, for centering the strip transversely in the leveller.

Guide rolls 30 may be adjustably spaced, in accordance with the strip width, and may also be adjusted right or left as viewed in Fig. 9, at constant spacing. To this end, the rolls are journaled to bearing blocks, such as 31a, which in turn are secured to yokes, such as 31b, these yokes in turn being suitably bored as at 31c, for slidable mounting on guide bars 31d, 31e. The yokes are also tapped as at 31f, for threaded engagement with adjusting shafts 31g and 31h, respectively. These shafts are threaded in opposite directions, as shown, shaft 31g in fact constituting a sleeve member rotatable on an extension of shaft 31h extending therethrough as at 31i. Keyed to shaft 31i is a hand wheel 31k while keyed to shaft 31g is a second hand wheel 31m. Thus, if the hand wheels 31k and 31m are rotated concurrently in the same direction, the guide rolls 30 will be displaced toward or away from each other, whereas if the hand wheels are rotated in opposite directions at constant speed, the guide rolls will be adjusted right or left at constant spacing, as viewed in Fig. 9.

The leveller B comprises in addition to the elements aforesaid (Fig. 10), a set 32 of three driven bottom rolls 32a, 32b and 32c journaled at their opposite ends in oppositely disposed stationary bearing blocks 32d and 32e (Figs. 10 and 11), and a set 33 of two driven top rolls 33a and 33b. The roller 33a is journaled in oppositely disposed end blocks (Fig. 11a) 34a-34a' and the roller 33b is similarly journaled in corresponding blocks 34b-34b'. The blocks 34a-34b at one end of the rollers are held together in a horizontal direction but permitted relative vertical movement by means of a dovetail connection designated 35 and the blocks 34a'-34b' are similarly held together by a like connection 35'. The connected blocks 34a-34b and 34a'-34b' are supported in aligned position and vertically adjustable in oppositely disposed end guides 36a-36b and 36a'-36b', respectively. The rollers 33a and 33b are individually movable up or down by mechanism now to be described.

The bearing blocks 34a-34a' are adjustably supported by respective shafts 37-37' (Figs. 10 and 11a) having threaded portions engaged in cooperating threaded bores provided in worm wheels, such as 39, which are in driven engagement with worms, such as 39a, secured to a worm shaft 41. The worm wheels 39a and shaft 41 are suitably journaled in stationary end frames 42a and 42b. Similarly, the blocks 34b-34b' are adjustably supported on shafts 38-38' cooperatively adjustable by means of worm wheels, such as 40a, driven by worms, such as 39a', secured to worm shaft 42. The worm shafts 42 and 41 are respectively driven by motors 43a and 43b (Figs. 8 and 10) to which they are suitably drivingly connected as by means of chain and sprocket drives 43d-43f and 43c-43e, respectively.

In order to facilitate the control of the raising and lowering of the bearing blocks 34a and 34b, means are provided for simultaneously energizing the motors 43a and 43b to raise such blocks, the latter being automatically stopped under the influence of pairs of limit-stop switches 44 and 45 (Fig. 11). The switches 44 and 45 are respectively provided with switch levers 44a and 45a which carry pivotally mounted on their outer ends cam rollers 44b and 45b in the path of movement of cam members 46 and 47, respectively, which are secured to the bearing blocks 34a and 34b, respectively. The cams 46 and 47, for example, are of the wedge variety and are ver-

tically adjustable by suitable screws, whereby the actuation of switches 44a and 44b may be properly timed.

Conversely, motors 43a and 43b are automatically stopped by the downward movement of the bearing blocks 34a' and 34b', respectively, by analogous mechanism including switches 48 and 49 having respectively switch arms 48a and 49a, cam rollers 48b and 49b and cooperating cams 50 and 51, respectively. Such cams are likewise adjustable vertically for timing the actuation of the switches 48 and 49.

As is well shown in Figs. 10, 11 and 13, the cams 46 and 50 are adjustably mounted on a bracket 52 which is rigidly secured to the bearing block 34a for movement therewith and there being adjustment screws 53 and 54 for fixing the position of the cam 50 upon such bracket and similar adjustment means for cam 46. In a similar manner the cams 47 and 51 are mounted on the bearing block 34b.

In addition to the aforementioned primary and secondary sets of leveller rolls, there are also employed a pair of leveller pinch rolls (Figs. 7, 8 and 9), such as 55 and 56. The former is preferably mounted for rotation upon a fixed axis but the latter can be raised or lowered. The top pinch roll 56 is mounted in suitable bearing blocks, such as 57-57'. The latter can be raised or lowered by means of a power cylinder, as at 58, which may be actuated by any suitable fluid medium. Preferably there are two such cylinders 58, one for each side of the apparatus.

The sets of rolls 32 and 33 and the pinch rolls 55-56 of the leveller unit are driven by means which will appear more fully below, for feeding the advancing strip end into the first grinder. When the strip gets into coiling position upon a winding reel, to appear hereinafter, the upper rolls are lifted to the position shown in Fig. 11 so as to clear the strip. The rolls of the leveller may or may not be continuously driven. Either the top and/or the bottom rolls can be power driven.

In the present embodiment the rollers of the leveller B (Fig. 1) are all driven by an electric motor 62 (Figs. 3 and 4) which is connected by a suitable gear box 62a and shaft connector 62b to a reduction gear box 62c from which splined and universal jointed shafts 62d, 62e and 62f serve to supply driving power to the three shafts 32a, 32b and 32c, and similarly shafts 62g and 62h and 62i and 62j serve to drive the upper leveller rolls 33a and 33b and the pinch rolls 55-56, respectively. An electric motor 62l drives suitable lubrication means for supplying lubricant to the drive train of motor 62.

GRINDING (UNITS C1-C6)

A typical grinding unit C1 is shown in Figs. 14-18 and will now be described. The strip S is first directed between a pair of superimposed entry pinch rolls 86, 87, the upper of which is mounted in stationary bearing blocks, and the lower of which can be raised or lowered by a pair of suitable power cylinders, one for each end of roll 87, one of which cylinders is shown as at 88, actuated, for example, by pneumatic or hydraulic fluid. Power cylinders 88 communicate thrust to their respective bearing blocks 87a of roll 87 via piston rods 88a. In the modification shown in the drawings, no drive is applied to these pinch rolls. The web passes thence convexly over a bottom pressure roll 89, the top surface of which is somewhat above the bite of the pinch rolls 86, 87. Thence the web 27 is passed beneath a hold-down roll 90, the rolls 86, 87, 89 and 90 being so positioned to cause the web 27 to travel convexly over the bottom pressure roll 89, thereby to present a convex surface substantially tangential to the opposed abrading element comprising in the modification, an endless belt 91 which is mounted to travel in a well known and conventional manner, upon three rolls consisting of a contact roll 92 which is opposed to and in vertical alignment with the bottom pressure roll 89, an idler roll 93 at the top of the three rolls, and a belt tension and takeup roll 94 which, in the form

10 shown, is mounted upon one arm of a bell crank 95, the latter being centrally pivoted at 96. The outer extremity of the opposite arm 95a thereof is pivotally connected as at 99, to a piston 98, operating in a pneumatic cylinder, to thereby provide for automatic belt tensioning by pneumatic pressure continuously applied to the cylinder and thus to the piston. (Selective belt oscillation is provided as by an oscillating cylinder 80 and oscillation adjustment 81.) Thus, the danger of stretching the belt edges is substantially eliminated thereby by adding greatly to the belt life.

15 The contact roll 92 preferably consists of a metal core having a rubber or rubber-like covering. The other rolls 93, 94 may be similarly covered if desired, but in the form shown are not.

In order to assist in controlling the tension of the strip S, the pinch rolls 86, 87 are provided with suitable brake means in the form shown comprising a friction brake having a brake shoe for the top roll 86, as at 100, and a shoe for the bottom roll, as at 101. Suitable hydraulically actuated means may be employed for controlling the pinch roll braking means comprising, for example, a power cylinder and piston device, as at 102, having a piston rod 103, which pivotally engages a brake arm 104. The latter is operatively connected with the aforementioned brake shoes 100 and 101. The pinch roll brakes are applied when the trailing end of the strip or web is about to clear the payoff reel. The tension upon the web can thus thereafter be maintained until the trailing end passes the last grinder. Two such braking means, one for each extremity of roll 86, may be employed.

20 A four-way valve 97a is provided for controlling the actuation of the power cylinder 97. As will be more particularly pointed out hereinafter, suitable manually controlled valves are provided respectively for controlling the braking of the top pinch roll and also for raising and lowering the bottom pinch roll; pressure meters are provided for indicating the pressure between the pinch rolls 86, 87 and also the pressure upon the pinch roll braking means; a pressure meter is provided for indicating the pressure on the bottom pressure roll 89.

25 The bottom pressure roll 89 is mounted for angular movement about a pivot, as at 105 (Fig. 14). Means are provided for quickly disengaging the bottom pressure roll 89 from the strips comprising, a pair of oppositely disposed arms 106 pivoted on the aforementioned pivot point 105, said arms supporting a pair of bearing blocks 107 for supporting opposite extremities of the bottom pressure roll 89. Quick disengagement of the rolls 89, 92 is obtained by means of a knee type toggle linkage, indicated generally at 108 (Fig. 14) and comprising upper and lower links 109 and 110, there being a pair 109, 110 for each side of the apparatus. Referring to Fig. 15, it is seen that the link 109 comprises two parallel side plates 109a and 109b of equal lengths secured at their extremities by pins which hold the same rigidly in spaced relationship. The upper extremities of the links 109 are pivotally secured, as at 111, to a yoke 107a which supports the bearing block 107. The lower extremities of links 109 are pivotally associated at the "knee" by means of pins, such as 112, with which the connection is made with the lower links 110 whose lower ends are pivotally secured, as at 113, to eccentrics 114 (Fig. 18). The angular movement of such eccentrics raise or lower by equal amounts opposite extremities of the bottom pressure roll 89 by means of the linkage 108.

30 The eccentrics 114 preferably are formed integrally, one on each end of shaft 117 which is drivingly connected to a geared electric motor 118 (Fig. 15) through the intermediary of the following interconnection: A chain and sprocket drive 118a, a shaft 119, a worm and wheel unit 120, a shaft 121 having therein a universal joint 122, and a second worm and wheel unit 123. A rapid disengagement of the rolls 89, 92 is effected

by quick bending of the knee of the linkage 108 through the intermediary of suitable power means comprising, for example, a pair of oppositely disposed pneumatic power cylinders 115 having pistons, such as 116, which are secured to the pins 112 (Fig. 15), there being two such cylinders 115, one for each side of the apparatus. The power cylinders 115 are actuated by four-way air valves provided with actuating solenoids under push-button control. Pneumatic actuators are preferred for this purpose to provide a desired degree of yield.

In addition to the aforementioned movement of the bottom pressure roll 89, the entire so-called abrasion head, including all of the rolls 92, 93 and 94 of the grinding unit, may be raised or lowered by suitable means including a screw-shaft 85 actuated by an electrical "screw-down" motor under push-button control (not shown) for adjusting to the thickness of the strip being ground.

The contact roll 92 is power driven (Fig. 15) by means of a motor 124 through the intermediary of V-belts 125 which engage suitable pulleys 124a, 124b.

In order to obtain an even grind, there may be an adjustment made, by suitable means, of the extent to which the links 109, 110 (on respectively opposite sides of the machine) may be moved to the right (Fig. 14). That is, the degree of separation of the opposite extremities of the rolls 89, 92 can be controlled to keep the rolls in parallelism by individual control of the extent to which the pins 112 may be moved to the right. This is accomplished by means of wedge-shaped cams 126 and 127, respectively, on the left and right sides of the machine (Fig. 16). Such wedge-shaped cams are shiftable axially, that is, transverse to the direction of movement of the web S, for example, by means of a threaded shaft 128 which is journaled at 129, 130 in the frame of the grinder. The threads, as at 128a and 128b (Fig. 16), respectively engaging the cams 126, 127, are cut in the same direction so that a given angular shift of the shaft 128 about its axis will move the cams 126, 127 in the same axial direction and since the cams are inclined oppositely, one of the linkages 108 (Figs. 14-15) will be allowed increased and the other decreased lengthening movement, and in this way the pressure roll 89 may be adjusted into parallelism with the contact roll 92.

In the embodiment shown in Figs. 1-2, and also Fig. 14, the grinding process is a so-called "wet" process, there being a plurality of belts, one on each of the grinding units, usually of varying grain sizes to produce the desired grinding results. A lubricating agent is directed upon the strip (or the belt) in order to assist the grinding process, such lubricating agent comprising, for example, a soluble vegetable and/or mineral oil.

A splash pan or shield, as at 131 (Fig. 14), is employed for receiving from a series of nozzles 132 a liquid spray, as at 132a, which carries abrasive particles and particles of metal down into a catch pan 133 where they are washed away. An arcuate inner cover, as at 134, extends from the upper end of the catch pan 131 over the top roll 93 and down to a catch pan 135, also for the purpose of catching and washing away the abrasive particles and particles of metal.

A spray, for example, of oil or any suitable liquid may be directed into the catch pan 135 by nozzle means 135a. Preferably a suitable coolant spray may be directed (by means not shown) upon the strip in between the various grinding units C1-C6.

A fume exhaust system is employed for drawing off dust and fumes from the otherwise airtight housings of the various grinding units. This is well shown in Figs. 19, 20 and 21 wherein a manifold 149 is provided having seven feeder conduits 150 in communication with the various housings of the grinder units. A power driven blower 151 (e. g. 9,000 C. F. M.) is centrally connected to the manifold 149 by means of a larger conduit 152 having a valve 153 therein. The blower 151 directs the

dust and fumes into a hopper 154 having a conical bin portion 154a with a suitable outlet 155 in the bottom thereof. A stack 156 is mounted above the hopper 154 through which the fumes from the grinding units escape.

SCRUBBER UNIT

The strip S after passing out of the last grinding unit C6 (Fig. 2) is directed to a scrubber unit D employing, for example, a pair of heavy wire brushes 137, 138. Such brushes are mounted in a frame (not shown) which holds their axes horizontal and parallel, the frame being mounted for angular movement about an axis transverse to the strip movement. Such angular movement is effected by an hydraulic cylinder device 136 under control of a four-way manually actuated valve (not shown). Such brushes are power driven and, if desired, a kerosene spray is directed upon one or both of them to assist the cleaning. Suitable scrubber unit pinch rolls 139, 140 are provided which are separably mounted. For example, the top pinch roll 139 may be raised or lowered through the intermediary of a power cylinder 141 actuated as explained below. The scrubber unit removes grit, sludge and grinding compounds from the web, thereby to permit the latter to proceed to the next unit, wiper E, in an uncontaminated condition.

WIPER UNIT

The wiper E employs a suitable drag wiper element, as at 143, for wiping off all remaining foreign matter, e. g., cleaning fluid. Drag wiper element 143 can be raised or lowered by a vertical threaded shaft 144 having a hand wheel 145 secured to the top extremity thereof. The drag wiper element 143 also urges the strip down upon a delivery end break-over billy roll 146 from which the strip passes to a winding unit F to be hereinafter described.

The billy or deflector roll 146 is preferably connected to a pilot generator which provides electrical energy which is a measure of line or strip speed. Such electrical energy may be employed for "synchronizing the line speed," that is, for synchronizing the speeds of certain of the roll driving motors whereby the surface speed of the rolls is the same as the surface speed of the strip.

WINDUP UNIT (F)

The recoiler or windup unit F comprises (Figs. 22-24) a main frame, generally designated as 181, on which is mounted a windup motor 182 suitably drivingly connected by a gear train in gear box 183 to a windup reel 184 of the conventional expandable segment type having an actuating fluid motive means, generally designated 185 (Figs. 23, 24), for expanding and gripping a windup coil 186 of the strip S. A power brake, designated in general as 187, is provided for braking the motor shaft and connected reel 184 and is operated by a fluid motive means, generally designated 188. Beneath the windup reel 184 is provided (Figs. 2 and 29) a coil hoist buggy 189, displaceable on tracks 189a, having mounted thereon a pair of blocker rolls 190 for supporting engagement with the coil 186 to be removed from the reel 184. On the under side of the coil hoist buggy is mounted an hydraulic cylinder 189b (Fig. 29) within which is displaceable a ram 189c supporting the blocker hoist 189, in which is received the wound coil 186. A stripper plate 191 is suitably mounted for movement axially of the reel 184 and is disposed for engaging the inner end of the coil 186. Suitable fluid motive means, designated generally as 192, is provided for actuating the stripper arm to eject a wound coil from the reel 184, when the latter is contracted, and on to the hoist 189. A suitable lubricating system for this unit F is operated by an electric motor and is generally designated as 181l.

CONTROLS

Referring to Figs. 1 and 3, the major controls for the equipment are mounted on main control panels I and II,

positioned respectively, adjacent the delivery and entry ends of the grinding line, with auxiliary control panels, as at III, mounted in front of each of the grinder units. Certain of these controls are electrical and others hydraulic or pneumatic.

Hydraulic controls

The hydraulic controls will first be described with reference to Figs. 1, 2 and 29. Thus, referring to the entry end main control panel II, Fig. 1, in conjunction with Fig. 29, there is provided on this control panel a manually actuated, four-way hydraulic valve 75, which functions to raise and lower the upper pinch roll 56, of the leveller unit B, through the intermediary of the hydraulic cylinder and piston assemblies 58. To this end, hydraulic pressure and exhaust lines 250, 251, extend respectively from main pressure and exhaust lines 252, 253 to the four-way valve 75, from which also extends lines 254, 255 to the upper and lower ends respectively of the cylinders 58. Actuation of the control handle 256 to one of two positions raises the pistons 58a in conventional manner, while actuation of the handle to its other position lowers these pistons, thus to elevate or depress the pinch roll 56 carried thereby. A corresponding actuation of a similar control valve 76 actuates the hydraulic ram 257 for raising or lowering the blocker hoist 24 mounted beneath the payoff reel 22. To this end, valve 76 is connected to the main pressure and exhaust lines 252, 253, over lines 258, 259, and thence over pressure and exhaust lines 260, 261 to the cylinder of ram 257. A similar valve 77, controls the actuation of the hydraulic motor 22e, 22d, for effecting expansion and contraction of the segments of the payoff reel 22, thereby to tighten or relax its engagement with the coil 23. To this end, valve 77 is connected to the main pressure and exhaust lines over lines 262, 263, and thence to the hydraulic motor 22d, over lines 264. Over equivalent connections a valve 78 actuates the hydraulic cylinder and piston assemblies 25, 25a for axially displacing the payoff reel 22 in or out to a desired extent, and maintaining it thereat until the control valve 78 is further actuated. A valve 78a is similarly connected for actuating the hydraulic motor 27h, 27g for manipulating the hold-down arm 27 of the payoff reel unit.

Referring now to the main control panel I at the delivery end of the line, Fig. 2, in conjunction with Fig. 29, there is mounted therein a control valve 235 for actuating the hydraulic ram assembly 189b, 189c, mounted on the underside of the delivery end blocker hoist buggy 189. The line connections 265, 266 to the valve for effecting this are the same as those for valve 76 above described. A valve 236 controls the hydraulic actuator 185 for expanding and contracting the delivery end of reel 184. A valve 237 actuates the hydraulic cylinder and piston assembly 267 for displacing the delivery end hoist buggy 189 along tracks 189a, thus in conjunction with the stripper arm 191 to remove the wound coil 186 from the recoiler reel 184. The stripper arm 191 in turn is actuated under control of valve 238 through the intermediary of the hydraulic actuator 192. A valve 238a controls the hydraulic actuator 141 for raising and lowering the upper delivery pinch roll 139 of the scrubber unit D.

On each of the auxiliary grinder control panels III there is mounted a control valve 204, for operating and releasing the hydraulic actuator 102, Fig. 14, for applying and releasing braking action to the upper entry grinder pinch roll 89. And there is also mounted on each of these panels a control valve 205 for operating the hydraulic actuators 88 of the lower grinder entry pinch roll 87, Fig. 14, for lowering or raising these rolls.

Referring further to Fig. 29, hydraulic pressure is maintained in the main pressure line 252 by means of motor driven pumps as at 268, in conjunction with a pressure reservoir 269. The main exhaust line 253 returns the hydraulic medium, in this case oil, to a sump 270 from

whence it is withdrawn and forced back through the pumps 268 into the main pressure line 252.

Electrical controls

5 Mounted on the control panels are various electrical controls, the majority of which will merely be designated as to function, inasmuch as they pertain to features of operation with which the present invention is not concerned. Thus, referring to the main entry control panel 10 II, there is provided: a line master control switch 59, for providing over-all control for the equipment; an entry end thread set-up pushbutton switch 59' employed for low speed operation in threading the strip through the line; payoff reel and leveller "jog" control pushbutton switches 69 and 61, for jogging these units forward or reverse during threading; ammeters 63 and 64 for indicating the load currents through the leveller roll motor 62 and the payoff reel motor-drag generator 21a; a volt meter for the payoff reel motor-drag generator; pairs of pushbutton switches 66 and 67, in circuit with the leveller "screw up" and "screw down" motors 43a and 43b, one pair for energizing said motors to raise the rolls 33a and 33b and the other pair for reversing the motors to lower these rolls. The payoff reel 22 can be driven either in a clockwise or counterclockwise direction, by current reversal through the armature, depending on whether or not the reel is to payoff in the "over" or "under" condition. For this purpose the direction of rotation of such payoff reel can be controlled by a selector switch 68 from the control panel 15 which effects current reversal through the motor armature. An emergency stop button for all electrical motors of the equipment is provided at 69. If desired a signal button for communication with the delivery end of the apparatus 20 may be provided at 70. A payoff reel tension rheostat 71 is provided in shunt with the armature of the motor-drag generator 21a to vary the drag generator load thereon, thereby controlling its braking action. A tension selector switch, as at 72, is provided for tandem operation and also an analogous switch, namely, a leveller selector switch, is provided at 73 for tandem operation. A payoff 25 reel selector switch for tandem operation is provided at 74.

On the delivery end, control panel I is provided the following electrical controls: A series of "start-stop" pushbuttons 211-216, incl., for actuating solenoid operated air 30 valves controlling the hydraulic cylinders and pistons 115 (Figs. 14-15), for raising and lowering the bottom pressure rolls, such as 89, of the respective grinder units. These pairs of pushbuttons are in circuit respectively with a corresponding pair of pushbuttons 201, mounted on the 35 corresponding control panels III, individual to the grinders, so that the raising and lowering of the rolls in question may be effected either from the delivery control panel I or from the auxiliary control panels III.

Ammeters 217, 218 are connected to the payoff reel 40 motor 21a and to the leveller roll motor 62, respectively, to indicate the loads thereon. Correspondingly, an ammeter 219 is in circuit with the windup reel motor to indicate the load thereon. There is also provided a voltmeter 220 connected with the windup reel motor 182 for indicating the voltage thereacross. Meters 223, 224 serve to indicate the operational speed of the leveller unit B and of the line, respectively.

A "jog" switch 223 is provided for the winding reel motor. An "Off" and "On" switch 224 is provided for 45 controlling the motor of the exhaust fan or blower 151 (Fig. 19). An emergency stop button 225 and a signal button 226 are provided at this station, corresponding to buttons 69 and 70, respectively at the entry station. A rheostat 227 serves to control the leveller speed. A release thread set-up switch and signal light are jointly 50 identified at 228. This switch has a back contact in series with a relay energized by the entry end thread up pushbutton 59' at the entry end station II.

A rheostat 229 is provided for adjusting the drag generator action of the payoff reel motor, for appropriately 55

tensioning the strip, and serves a similar function to rheostat 71 at the entry station II. Suitable "Start" and "Stop" buttons 230 are provided for the scrubber unit (Fig. 2). An "Over" and "Under" selector switch 231 provides current reversal through the armature of the winding motor for reeling the strip in the "Over" or "Under" condition as desired.

A control switch 232 is provided for suitably adjusting the voltage until the line speed has reached a maximum predetermined speed. A switch 233 serves to select "jog" or "run" conditions for the windup reel, corresponding to switch 74 at the entry station II. A line master control switch 234 is provided, corresponding to switch 59 at the entry station II.

On each of the auxiliary control panels III, are provided the following electrical and other controls in addition to the hydraulic controls above described: A counter 195 (Fig. 15) is connected to screw 85 for indicating the opening between the contact roll 92 and the pressure roll 89, and control buttons 196 are connected for actuating the screw-down motor (not shown) for driving screw 85 to adjust the operation between rolls 89, 92. An ammeter 197 is suitably connected for indicating the amount of grinding pressure. "Start" and "Stop" buttons 198 are connected for actuating the contact roll drive motor 124. A signal light 199 serves to indicate oscillation of the grinding belt 91 (Figs. 14-15). A lockout selector switch 200 is provided for disconnecting from the automatic line control, the grinding unit controlled from this panel. Switches 201 serve to energize solenoids for operating air valves connected to the cylinders 115 (Figs. 14-15) for raising and lowering the bottom pressure roll 89. Control "Start" and "Stop" buttons 202 are provided for actuating the motor 118 for fine adjustment of bottom pressure roll 89, to effect the precise degree of grinding desired. Line master start and stop buttons 203, are provided for line control on any grinder unit panel. Depression of the line stop button 203 at any grinder station III, will cause all grinder pressure rolls 89 to drop. Depending on the prior circuit conditions effected by the actuation of the other controls this depressing of the line stop pushbutton 203, in one case will stop only the entry end of the line and in other cases will stop the entire line, in addition to dropping the lower grinder pressure rolls.

The only electrical circuits of the equipment which require detailed description are the basic controls for the reel and leveller drive motors, discussed below with reference to Fig. 30. All of the remaining electrical motors operate at constant speed over conventional circuits under pushbutton control, for starting, stopping and, in certain instances, also reversing, as in the case of the motors 43a, 43b, Fig. 8, for raising and lowering the upper leveller rolls. All such motors are direct current operated except the grinder head motors, which are of the three-phase induction type.

Likewise, the control circuits for the pneumatic motors, such as those for raising and lowering the grinder contact and lower entry pinch rolls, require no detailed description as they are likewise conventional. In each the action is under control of a solenoid actuated four-way pneumatic valve, having separate pushbutton actuated solenoids for raising and lowering the roll in question, the pneumatic action being similar to that of the hydraulic action described with reference to Fig. 29 for the manually actuated hydraulic valves.

Referring to Fig. 30, wherein like elements corresponding to those shown on the control panels I-III, incl., Figs. 1 and 2 are similarly designated, the payoff reel motor drag generator, shown generally at 350 and the leveller motor shown generally at 351, receive armature current from the "Generator No. 1" shown generally at 352; while the winding reel motor shown generally at 353, receives armature current from "Generator No. 2," shown generally at 354. Generator 352 comprises a

field winding 355, which is connected between main direct current power supply bus bars 356, 357, through one or the other of the adjustable rheostats 358, 358a, as discussed below, for varying the current in the generator field winding. The armature 359 of this generator is connected between the negative bus bar 357 and thence through the front contact and armature 361A of a master control relay 361, and thence to auxiliary bus bar 362. The winding of the master control relay 361 is connected from the negative bus bar 357 and thence to the positive bus bar 356, through normally open contacts of parallel connected "Start" buttons 59, 234. When one of these "Start" buttons is depressed, it thus completes an energizing circuit for relay 361 which thereupon operates, and immediately locks up through its normally open back contact and armature 361B to the positive bus bar 356 through the normally closed contacts in series of "Stop" buttons 69, 225. This operation of the master control relay 361 thus connects the generator armature 359, directly between the negative bus bar 357 and the auxiliary bus bar 362.

The payoff reel motor-drag generator 350, designated 21a in Fig. 1, comprises an armature 366 and associated field winding 367. The field winding is bridged directly between the main power bus bars 356, 357, through an adjustable rheostat 368 for adjusting the current in the field winding. The armature 366 is bridged at points 369, 370 between a pair of conductors 371, 372. Conductors 371, 372 are in turn strapped together at their opposite termini by conductors 373, 374, respectively, which strapping conductors are in turn respectively connected to the auxiliary bus bar 362 and the main negative bus bar 357, over connections 375, 376. Interposed in the upper conductor 371 between point 369 and the strapping conductor 373 are normally open contacts A-1 of a relay A, while interposed in the upper conductor 371 between point 369 and the strapping conductor 374 are normally open contacts B-2 of a relay B. Likewise between the lower junction point 370 and the strapping conductor 373 are interposed normally open contacts B-1 of relay B; while interposed between this junction point and the strapping conductor 374 are normally open contacts A-2 of relay A.

Relays A and B are in turn connected in energizing and release circuits, respectively, as follows: An energizing circuit for relay A is traced from the auxiliary bus bar 362 over a connection 377, thence through contacts of a normally closed "stop" pushbutton 378, thence through normally open contacts of a "Forward" pushbutton 379, thence through the upper rotary arm and fixed contact 381 of a rotary gang selector switch 68, thence through the A relay winding and over a connection 383 to the negative bus bar 357. A corresponding operating circuit for relay B is traced from the auxiliary bus bar 362, over connection 377 through the "Stop" switch 378, thence through normally open contacts of a "Reverse" switch 384, thence through the lower rotary arm and fixed contact 386 of gang switch 68, thence through the B relay winding and over connection 383 to the negative bus bar 357. It will thus be seen that with the gang switch set as described, if the upper or "Forward" pushbutton 379 is depressed, relay A will operate; while if the lower or "Reverse" pushbutton 384 is depressed, relay B will operate to transmit current in one direction or the reverse through the motor armature 366, through contacts A-1, A-2 of relay A, or through contacts B-1, B-2 of relay B. In this way, the payoff reel motor is rotated in one direction or the opposite, depending on which pushbutton 379 or 384 is depressed. Alternatively, if the gang switch is rotated so that its upper and lower rotary arms contact, respectively, the fixed contacts 387, 388, then upon depression of the "Forward" pushbutton 379, relay B will now operate; while depression of the "Reverse" pushbutton 384 will now operate relay A, since these relays are reversely connected to the fixed contacts

387, 388, as compared to their connections to fixed contacts 381, 386. Thus the "Forward" and "Reverse" directions of motor rotation are reversed as compared to that initially described. By appropriate setting of the selector switch 68, the motor will be so rotated in the "Forward" direction as to cause the payoff reel to "pay over" or "pay under" as desired.

The "Forward" and "Reverse" pushbuttons 379, 384, are so arranged either by mechanical interlocking with the "Stop" button 378, or by means of interposed relays, that once either of the "Start" or "Reverse" buttons is depressed, the motor armature will continue to be energized until the "Stop" pushbutton 378 is depressed to open the energizing circuits above traced. Depression of the "Stop" pushbutton 378 restores all circuits to the normal condition as shown in the drawing.

For providing dynamic braking or drag generator action, there is bridged between the upper and lower conductors 371, 372 of the motor armature circuit, a pair of rheostats 71, 229, one mounted on the entry control panel II, Fig. 1, and the other on the delivery control panel I, Fig. 2. The rotary arms of these rheostats normally rest on open contacts as shown, rotation slightly from which bridges the rheostat 71 or 229 across the motor armature, thus adjustably to load the armature, depending on the rheostat setting, and thereby apply dynamic or regenerative braking.

The operating circuits for the leveller motor 391 are generally similar to those described for the payoff reel motor. Here again the motor armature 391 is bridged between upper and lower conductors 392, 393, which are strapped at their ends as shown, and thence connected, respectively, over conductors 394, 395 to the auxiliary and main bus bars 362, 357. The upper and lower conductors 392, 393 contain normally open contacts C-1 and C-2 and D-1 and D-2 of relays C, D, for operating the motor forward or reverse. To this end relay C is connected in series with normally open contacts of a "Forward" pushbutton 396 and thence through normally closed contacts of a "Stop" pushbutton 397 between bus bars 362, 357; while relay D is similarly connected in series with contacts of a normally open "Reverse" pushbutton 398 and the contacts of the "Stop" pushbutton 397 between bus bars 362, 357. Thus the leveller motor may be operated forward or reverse by simple depression of pushbutton 396 or 398. These pushbuttons are interlocked with the "Stop" pushbutton 397 as above described, so that depression of the "Stop" pushbutton releases any actuated button 396 or 398 and restores the circuit to normal.

Over-all speed control for the armatures of the payoff reel and leveller motors is obtained by adjustment of the rheostat 358 in series with the field winding 355 of generator 352. Individual speed adjustments for these motors may also be obtained by individual adjustment of the rheostats 369 and 399 in series with the field windings 367 and 400 of these motors, respectively.

To operate the payoff reel and leveller motors at low or threading speed, rheostat 358a, also in series with the generator field winding, may be connected by depressing the "threading" pushbutton 59a. During the threading operation the rheostat 358 is disconnected through switch 401.

Rheostat 402 in shunt to the leveller motor armature 391, permits of adjustable dynamic braking, as in the case of the payoff reel motor.

The circuit arrangement for the winding reel motor and the speed control thereof is substantially the same as for the payoff reel motor. That is to say, the direction of current flow through the motor armature 403 for forward and reverse, is controlled by the positioning of a gang selector switch 404, the setting of which determines whether relay E or relay F is operated by depression of the "Forward" pushbutton 405, and vice versa for the "Reverse" pushbutton 406, the relay contacts in

the motor circuit for effecting this are shown at E-1 and E-2 for relay E, and at F-1 and F-2 for relay F. As before, once pushbutton 405 or 406 is depressed, the motor will continue to operate in the corresponding direction of rotation until the "Stop" button 407 is depressed to restore all circuits to normal. The speed of rotation of the armature 403 of the winding reel motor is determined primarily by the setting of rheostat 408 connectible through switch 408a in series with field winding 409 of the generator 354, the armature 410 of which supplies the winding reel motor over connections extending between the auxiliary bus bar 411 and the main bus bar 357. Rheostat 420 provides threading speed through pushbutton 421. Further adjustment of the motor speed is obtained through adjustment of rheostat 422 in series with the field winding 423 of the payoff reel motor.

The armature of generator 354 is connected to the auxiliary bus bar 411 through a back contact and armature 361c of the master control relay 361. Hence all circuits are inoperative until one of the "Start" buttons 59, 234 of the master control circuit is depressed, and all circuits are restored to normal when one of the "Stop" buttons 69, 225 thereof is thereafter depressed.

OPERATION

In its essentials, and by the use of the control means previously described, the over-all operation of the apparatus in the surface grinding of strip is as follows (Fig. 1): The coil 23 of the strip S to be ground is delivered from the incline 26 on the rolls 24a of the blocker hoist 24 which is raised by control 76 and by means of controls 77 and 78 the payoff reel 22 is moved into supporting engagement with the coil and the coil is moved into register with the "pass line." The hold-down arm 27 is now moved into position by the control 78a (Panel II). The leading end of strip S is fed thence to the leveller unit B for flattening the strip and for feeding the strip end thence into the first grinding unit C. During this portion of the cycle, the vertical rolls 30 are suitably adjusted and the pinch rolls 55-56 are operated, and the upper set of leveller rolls 33 are arranged to engage the strip and press the same against the lower set of rolls 32 for flattening purposes, all in the manner previously described. During this stage the pinch rolls 55-56 and leveller rolls are driven, thus to feed the leading strip end forward into the first grinding unit, the payoff reel being likewise driven during this stage. The hold-down arm 27 performs its important function due especially to the fact that the reel is driven to positively unwind or uncoil the strip; which due to its stiffness would cause serious damage by uncoiling against an operator. As the leading strip end approaches the first grinding unit C1, the entrance pinch roll 87 and pressure roll 89 are lowered so that the strip end will pass freely between them and the opposed upper pinch and abrading contact roll, respectively. The strip end thus passes freely through the first grinder unit and out below the hold-down roll 90 thereof, whereupon the pressure and lower rolls are elevated to press the strip against the upper pinch and abrading contact rolls. Fine grinding adjustments are accomplished by motor 118 (Figs. 15 and 18).

In the same way, the leading strip end is fed successively into and through each of the remaining grinding units C2-C6, inclusive, of the sequence and thence (Fig. 2) through the scrubber D and wiper E and onto the wind-up reel 184. As soon as the leading strip end is locked in position on the winding reel, power is applied to the latter to drive the same, at which time regenerative braking is applied to the motor of the payoff reel, thus to tension the strip throughout the line. The desired line speed is effected by adjustment of line speed control switch 232, Fig. 2. During this portion of the cycle, the entrance pinch rolls and the leveller rolls may be idled or the upper rolls, 56 and 33a and b, Fig. 10, may

optionally be elevated away from the strip, since the tension now applied to the strip suffices for straightening purposes.

When now the strip has been fed through the grinding units to the point that the trailing end thereof is about to leave the payoff reel 22, braking action is thereupon applied to each of the grinder pinch rolls by means of fluid motors, such as 102. This serves as a means of maintaining tension on the strip as the trailing strip end passes successively through the grinding units from the first to the last of the sequence and thence through the scrubber and wiper units D and E onto the winding reel 184.

After the strip S is wound on reel 184 the blocker hoist 189 is raised into receiving position, stripper plate 191 is operated and the hoist may be moved transversely to the delivery point.

MODIFICATIONS

In Figs. 25-28, inclusive, we have shown certain modifications of the grinding units, as to abrasive elements and arrangement. Only such features as differ from the apparatus heretofore described will be specifically referred to in these modifications.

The embodiment of the grinding line shown in Fig. 25 is identical to that shown in Figs. 1 and 2, except that in lieu of the grinder units C1-C6, inclusive, there are employed a plurality of grinder units, such as 157, 158, 159. The grinder unit 157, which is typical, includes a pair of power driven pinch rolls 160 which are generally similar in function and operation to pinch rolls 86, 87 shown in Fig. 14 and have associated therewith drive and separation means which are also similar. Two grinding rolls are employed, 161, 162, each of which is similar to that shown in copending United States patent application Serial No. 294,576, now Patent No. 2,686,545. Thus each grinder unit 157-159 is capable of grinding both sides of the web 27. The path of the web shown in Fig. 25 is substantially horizontal, as viewed in this figure, although it may be sinuous or generally so if desired. Such sinuous path or web is shown in Fig. 26 wherein the grinding line is generally similar to that described in Fig. 25 except for the fact that only the upper of the rolls, as at 163, 166, inclusive, are grinding rolls, the rolls immediately therebeneath being bottom pressure rolls which may be mounted as above described in Fig. 14. The pinch rolls, as at 167, and 168, of Fig. 26, are mounted somewhat below the bottom pressure rolls whereby the sinuous web path is obtained as shown.

In the embodiment shown in Fig. 26 only the upper surface of the web is ground.

However, in the embodiment shown in Fig. 27 there is illustrated a combination of the endless belt type of grinder unit shown in Fig. 14, together with grinder units as shown in Fig. 26, there being two units, as at 169 and 170, which are similar to those shown in Fig. 26 and two additional grinder units 171 and 172 which are similar to that shown in Fig. 14.

In the embodiment shown in Fig. 28 a plurality of grinder units are shown which acting together are capable of grinding both sides of the web, said grinder units being generally similar to those shown at 169 and 170 in Fig. 27 with the exception that alternate grinder units have the grinder roll thereof on the opposite side of the web thereby to permit such grinding of both web sides. The grinder units are indicated at 173-178, inclusive, and are so disposed to provide a sinuous or generally sinusoidal path for the web S. The abrasion of the web occurs at the convex regions where the web is bent over the opposed pressure rolls. Suitable pinch rolls, as at 179 and 180, are provided at opposite extremities of the grinding path of Fig. 28.

Having thus described our invention with particular reference to the preferred form thereof and to certain modifications, it will be obvious to those skilled in the

art to which the invention pertains, after understanding our invention, that various changes and other modifications may be made therein without departing from the spirit and scope of our invention, as defined by the claims appended hereto.

What is claimed as new and desired to be secured by Letters Patent of the United States is:

1. In an apparatus for surface abrading an elongated strip of metal, the combination of: a payoff reel for rotatively supporting a coil of said strip; means for driving said payoff reel to unwind said strip; levelling means adjacent said payoff reel for receiving the leading strip end from said coil and feeding said strip forwardly while levelling the strip; a tandem arranged series of grinding units for successively receiving said leading strip end; each said grinding unit including in tandem, a pair of entry pinch rolls, a driven abrading roll and opposed pressure roll, and a hold-down roll, means for retracting said pressure roll relative to said abrading roll and means for retracting at least one said pinch roll relative to its opposed roll, means for braking at least one of said pinch rolls; a recoiling reel beyond said grinding units, for recoiling said strip; means for driving said recoiling reel for pulling the strip from said payoff reel through said grinding units; and braking means associated with said payoff reel, for tensioning the strip between the payoff and recoiling reels.
2. In an apparatus for surface abrading an elongated strip of metal, the combination of: a payoff reel for rotatively supporting a coil of said strip; means for driving said payoff reel to unwind said strip; driven levelling means adjacent said payoff reel for receiving the leading strip end from said coil and feeding the same forwardly while levelling the strip; a tandem arranged series of grinding units for successively receiving said leading strip end, each said grinding unit including in tandem, a pair of entry pinch rolls, a driven abrading roll and opposed pressure roll, and a hold-down roll, means for causing said pressure roll to engage said abrading roll under resilient pressure, and for retracting said pressure roll, means for advancing one said pinch roll into pressure engagement with the other and for retracting the same; a recoiling reel beyond said grinding units, for recoiling said strip; means for driving said recoiling reel for pulling the strip from said payoff reel through said grinding units; braking means associated with said payoff reel for tensioning the strip between the payoff and recoiling reels; and braking means associated with the entry pinch rolls of each said grinding unit, for maintaining tension on the strip as the trailing strip end of said coil passes off the payoff reel and successively thence through said grinding units.
3. In an apparatus for surface abrading an elongated strip of metal, the combination of: a payoff reel for rotatively supporting a coil of said strip; means for driving said payoff reel to unwind said strip; driven levelling means adjacent said payoff reel for receiving the leading strip end from said coil and feeding the same forwardly while levelling the strip; a tandem arranged series of grinding units for successively receiving said leading strip end, each said grinding unit including in tandem a series of horizontally disposed rolls comprising, a pair of entry pinch rolls, a driven abrading roll and opposed pressure roll, and a hold-down roll, means for causing said pressure roll to engage said abrading roll under resilient pressure, and for retracting said pressure roll, means for advancing one said pinch roll into pressure engagement with the other and for retracting the same, said abrading roll being disposed above the pass line of said entry pinch and hold-down rolls, whereby with said pressure roll advanced to press the strip against said abrading roll, said strip is arcuately flexed to provide a substantially tangential area of contact with said abrading roll; a recoiling reel beyond said grinding units, for re-

coiling said strip; means for driving said recoiling reel for pulling the strip from said payoff reel through said grinding units; and braking means associated with said payoff reel for tensioning the strip between the payoff and recoiling reels; and braking means associated with the entry pinch rolls of each said grinding unit, for maintaining tension on the strip as the trailing strip end of said coil passes off the payoff reel and successively thence through said grinding units.

4. The method of surface abrading an elongated strip of metal, by employment of apparatus comprising payoff and recoiling reels, having interposed therebetween in tandem, a leveling unit comprising a series of opposed intercalated rolls, and a series of grinding units, each including a pair of entry pinch rolls, a driven abrading roll and opposed pressure roll, and a hold-down roll, said method comprising: mounting a coil of said strip on said payoff reel, driving said payoff reel to feed the leading strip end forwardly toward said levelling unit while spacing the opposed rolls of said unit to receive the strip end therebetween, thereupon causing said opposed rolls to engage the opposed strip surfaces under pressure, while driving at least certain of said rolls to feed said strip forward toward said grinding units and to straighten the strip, retracting an entry pinch roll and said pressure roll of each grinding unit to receive the advancing strip end, and thereupon urging said entry pinch roll and pressure roll of each grinding unit against its opposed roll with the interposed strip therebetween while driving said abrading roll to surface grind the strip, receiving the leading strip end onto said recoiling reel and driving said reel to recoil the strip, while tensioning the strip between said recoiling reel and payoff reel by braking action applied to said payoff reel, and, as the trailing end of said strip passes off said payoff reel, applying braking action to the entry pinch rolls of each said grinding unit for maintaining tension on the strip as the trailing strip end of said coil passes off said payoff reel and successively thence through said grinding units.

5. A method according to claim 4 wherein said strip is arcuately flexed over the pressure roll of each grinding unit thereby to provide a substantially tangential area of contact with the opposed abrading roll, during grinding, thereby uniformly to abrade all surface portions of the strip.

6. In a grinding device for strip material: an abrasive endless belt; means rotatably mounting said belt comprising an idler roll, a contact roll and a tension control roll; a bottom pressure roll positioned for pressing such strip material against said belt on said contact roll; roll means for guiding such strip material convexly over said pressure roll and in tangential contact with said abrading belt; means for mounting said pressure roll for movement away from and toward said contact roll comprising, a pair of knee linkages, one for each end of said pressure roll, for controlling the position of the latter relative to said contact roll, adjustable limit-stop means for each of said linkages, said limit-stop means holding said knee linkages slightly bent when the latter is in the extreme position thereagainst; and means for yieldingly urging said linkages toward such extreme position.

7. In a grinding device for strip material, the combination of: an abrading roll and a pressure roll positioned for pressing such strip material against said abrading roll; means for mounting said pressure roll for movement away from and toward said abrading roll comprising, knee-toggle linkage means for removably positioning said pressure roll in abrading position, having means for actuating said linkage, and adjustable wedge means movably positioned for adjustably limiting the position of said knee-toggle linkage means in said abrading position.

8. In a grinding device for strip material, the combination of: an abrasive endless belt; means for holding such abrasive belt comprising an idler roll, a contact roll and a tension control roll; a bottom pressure roll posi-

tioned for pressing such strip material against said belt on said contact roll; roll means for guiding such strip material convexly over said pressure roll thereby to bend same convexly to provide a region of abrasion; means for mounting said pressure roll for movement away from and toward said contact roll; knee-toggle linkage means for removably holding said pressure roll in abrading position; adjustable wedge means movably positioned for controlling the position of said knee-toggle linkage in said abrading position; and additional means connected to said toggle linkage for effecting fine adjustment of said pressure roll toward and away from said contact roll.

9. In a grinding device for strip material, the combination of: an abrasive member mounted for movement about an axis of rotation; a pressure roll positioned for pressing such strip material against said abrasive member; roll means for guiding such strip material convexly over said pressure roll thereby to bend same convexly to provide a region of abrasion; means for mounting said pressure roll for movement away from and toward said abrasive member; knee-toggle linkage means for removably holding said pressure roll in abrading position; adjustable wedge means movably positioned for controlling the position of said knee-toggle linkage in said abrading position; and additional means connected to said toggle linkage for effecting fine adjustment of said pressure roll toward and away from said abrasive member.

10. In apparatus for abrading an elongated strip of sheet metal comprising an abrasive member mounted for movement about an axis of rotation transverse and substantially parallel to the path of said strip and a pressure roll for urging said strip against said member; the combination with said pressure roll of linkage means disposed at respectively opposite ends of said pressure roll for holding said roll in operative position toward said abrasive member and quickly displacing said roll from operative position; means for reversely adjusting the position of said linkage on respectively opposite ends of said pressure roll to adjust said roll to parallelism with said abrasive member; and means for simultaneously and equally raising and lowering said oppositely disposed linkage to thereby effect fine adjustments of said pressure roll to vary the degree of abrading.

11. In apparatus for abrading an elongated strip of sheet metal comprising an abrasive member mounted for movement about an axis of rotation transverse and substantially parallel to the path of said strip and a pressure roll for urging said strip against said member; the combination with said pressure roll of journal means pivotally mounted for swinging movement about an axis spaced from and substantially parallel to the axis of said roll; a pair of knee-toggle linkages having their upper ends pivotally connected to said journal beneath said roll adjacent its respectively opposite ends, said linkages having their lower ends pivotally mounted on rotatable eccentric means for effecting small increments of movement of said roll when said toggle linkages are in extended position; pneumatic actuating means operatively connected adjacent the knees of said linkages for yieldably urging them to extended position; cam blocks slidably disposed behind said knees respectively to limit the extended movement of said linkages by said pneumatic means; and means for moving said cam blocks so as to oppositely vary the movement of respectively opposite knees, whereby said roll may be adjusted to parallelism with said abrasive member.

12. Apparatus for abrading an elongated strip of sheet material having in combination: a payoff reel device for holding a coil of such strip, braking means for such reel; a power driven winding reel device for taking up such strip unwound from said payoff reel; means interposed between said reels for acting on such strip comprising: a leveller roll unit for flattening and feeding the strip from the payoff reel to other of such means, such leveller unit including a set of lower rolls and a set of upper rolls,

at least one of said sets of rolls being movable relative to the other set, a plurality of grinding units providing a sinuous path for the strip to be ground and including a plurality of roll members over which the strip moves arcuately to provide convex abrasion regions, and a like plurality of movable abrasive members for engaging such strip at such convex regions, means for directing a liquid upon said strip at such regions of abrasion, means for cleaning such strip prior to winding same upon said winding reel, and means for controlling said power driven winding reel for controlling the tension upon such strip in such sinuous path.

13. The method of surface grinding an elongated strip of metal, which comprises: rotatably mounting a coil of the strip at a first station, positively rotating said coil progressively to uncoil the strip and feed the leading strip end to a second station, concurrently straightening and progressively feeding the strip at said second station, thence successively to each of a series of grinding stations, progressively surface grinding the strip at each grinding station, engaging the leading strip end at a coiling station beyond the last grinding station, and positively winding the same into a coil thereat, and during said winding, tensioning the strip between said coiling and uncoiling stations.

14. The method of surface grinding an elongated strip of metal, which comprises: rotatably mounting a coil of said strip at a first station, positively rotating said coil progressively to uncoil the strip and feed the leading strip end to a second station, concurrently straightening and progressively feeding the strip at said second station, thence successively to each of a series of grinding stations, progressively surface grinding the strip at each grinding station, while positively feeding the same thereat, thence toward the next and succeeding grinding stations, engaging the leading strip end at a coiling station beyond the last grinding station, and positively winding the same into a coil thereat, and, during said winding, tensioning the strip between said coiling and uncoiling stations, by cessation of the positive feed at said coiling station and retardation of the uncoiling of the coil thereat.

15. A method according to claim 14 which includes

the additional steps of retarding at each grinding station, the movement of the strip therethrough as the trailing strip end passes from said coiling station successively through said grinding stations.

5 16. The method of grinding an elongated strip of metal, which comprises: rotatably mounting a coil of said strip on a substantially horizontal axis, unwinding said strip from said coil and propelling the leading end of said strip through the first of a series of grinding stations, and 10 thence to succeeding such stations, applying positive feed to the strip at each successive grinding station to feed it to the next successive grinding station, subjecting the strip to successive grinding operations at said stations, engaging and feeding said strip beyond the last of said grinding stations and positively winding the same into a coil with torque sufficient to place the strip under tension and pull the same through said grinding stations, and during said winding, so regulating the unwinding of said strip as to tension the strip throughout.
